LATERAL MOVING TABLE LEG FASTENER

Folke Ohlsson, Malmo, Sweden; assignor to Kocks
Snickerifabriker Aktiebolag, Trelleborg, Sweden, a corporation of Sweden

Application March 23, 1948, Serial No. 16,565
In Sweden December 3, 1947

4 Claims. (Cl. 311—112)

1

This invention relates to furniture having body portions and easily mountable and removable leg means thereon. More particularly the invention relates to a new type of lateral moving table leg fastener.

The principal objects of the invention are to provide novel means for attaching the leg means to the body portion of a piece of furniture in a manner allowing easy mounting and removal of the leg means by simple tools; to provide a new and very rigid connection between the body portion and the leg means of a piece of furniture; to provide a novel connection between the body portion and the leg means of a piece of furniture allowing subsequent tightening of the connection for compensating possible drying of the wooden body portion and leg means in a manner involving only slight displacement of the leg means in lateral direction; and to provide inexpensive means for connecting the body portion and the leg means of a piece of furniture.

Other objects and advantages of the invention will be clear from the following description of some preferred embodiments of the invention shown on the accompanying drawings in which

Fig. 1 is a perspective view of an improved table according to the invention provided with a shelf for newspapers etc.

Fig. 2 is a vertical section of part of the table-top of the table shown in Fig. 1, taken adjacent one of the legs.

Fig. 3 is a section on line III—III in Fig. 2.

Figs. 4 and 5 are views similar to Fig. 2 showing different modifications of the invention.

Fig. 6 is a perspective view of another type of table, and

Fig. 7 is a detail view of how the legs are attached to this type of table.

Referring to the drawings, the table shown in Figs. 1 to 3 comprises a quadrangular table-top 1 with rounded-off corners and with a leg 2 at each corner. The table-top is relatively thin and has a border member 3 extending around the table along the edges thereof. At each corner of the table-top there is mounted, on the underneath side thereof, a corner block 4 of the same height as the border member 3 and extending between the sides of the border member running from the corner, in such a way that an aperture 5 is formed between the corner portion of the border member and the corner block 4.

On the body portion of the piece of furniture formed by the table-top 1, the border member 3 and the corner blocks 4, the legs 2 are easily mountable and removable in the following man-

ner. Each leg 2 at the top has a horizontal stop face 6 from which a tenon 7 that is preferably integral with the legs 2 extends upwards approximately from the center thereof, so that said stop face 6 surrounds the tenon 7 on all sides; as is best seen from Fig. 3 in which the contour of the stop face 6 is indicated by means of a dash and dot line 8. On the whole, the tenon 7 has the same general cross sectional form as the aperture 5 but has smaller cross sectional dimensions than the latter, whereby the tenon may be introduced therein. On the side facing the corner block 4 the tenon 7 has three parallel surfaces 9 and three parallel surfaces 10, of which the surfaces 9 are inclined in relation to the longitudinal axis of the leg 2 and are turned downwards, while the surfaces 10 are inclined in relation to the longitudinal axis of the leg and are turned upwards. The surfaces 10 are approximately at right angles to the surfaces 9 and alternating therewith, so that the said side of the tenon 7 has a toothed appearance, as seen in the vertical section according to Fig. 2. The corner block 4 has its side facing the tenon 7 formed accordingly, viz. with inclined surfaces 11 and 12, respectively, alternately turned upwards and downwards, the surfaces 11 of which are adapted to bear against the surfaces 9 of the tenon 7. In the side of the tenon remote from the corner block 4 there is countersunk a nut 13 or a plate with a threaded hole therein, into which a spindle 14 that is threaded at both ends and passes through the tenon 7 and the corner block 4, may be screwed after the tenon 7 has been inserted in the aperture 5. After this a nut 15 is screwed onto the end of the spindle 14 projecting out of the corner block 4 and can be tightened against the corner block 4 so that the tenon 7 is firmly pressed against the block 4, whereby the tenon and the block will bear against each other through their inclined surfaces 9 and 11. Since the compressing force exerted on the spindle 14 and the nut 15 is directed obliquely to the bearing surfaces 9 and 11, the tenon 7 will tend to move obliquely upwards, a sliding occurring thereby between the surfaces 9 and 11, whereby the stop face 6 of the leg 2 is firmly pressed against the underneath side of the border member 3 and the corner block 4. Thereby a very solid fastening of the leg 2 to the table top 1 is obtained solely by tightening the nut 15. If the wood should dry after the original fastening of the legs 2, so that they will become loose, it is very simple to firmly fasten the legs again by tightening the respective nuts 15.

3

The fastening of the legs 2 described above is not only just as simple and firm as when applying the methods, hitherto known, of fastening mountable and removable legs by means of wedges with backed-off wedge surfaces arranged on the legs and correspondingly formed wedge grooves provided in the table-top or the like, but in certain cases the invention has the important advantage over the wedge connection in that the legs to be firmly fastened after the wood has dried out do not need to be displaced through any appreciable distance in horizontal direction as distinguished from the case where using the wedge connection. This is of great importance when it is desired to mount for instance a shelf 16 for newspapers between the legs of the table, as is shown in Fig. 1, for if the legs 2 in such a construction have to be moved a considerable distance towards or away from each other for compensating the drying of the wood, it would be impossible or at any rate very difficult to fasten the newspaper shelf 16 in such a way as to permit the necessary displacement of the legs without the shelf being loosely secured to the legs in some adjusted position.

The inventive idea defined by the claims can be realized in many ways other than that shown in Figs. 1 to 3. Three different alternatives are shown by way of example in Figs. 4 to 7.

The embodiment according to Fig. 4 substantially corresponds to that according to Figs. 1 to 3, and Fig. 4 merely serves the purpose of illustrating how it is possible to provide a sufficiently large stop face 28 to bear against the underneath side of the border member 29 and also the corner block 30 when the legs 31 are slender and consequently the tenon 32 provided with inclined surfaces for co-operation with the corner block 30 has to be made approximately as thick as the legs for reasons of solidity. In the embodiment according to Fig. 4 the stop face 28 is formed on a loose plate 33 passed over the tenon 32 and bears against a small shoulder 34 on the leg 31, from which the tenon 32 projects approximately centrally.

In the embodiments according to Figs. 1 to 4 the hole 35 for the rod 14 and 25, respectively, in the corner block 4 or 30 and in the angle piece 26, respectively, is oblong or formed with a sufficiently large diameter in order that the rod 14 and 25, respectively, may participate in the movement of the leg 2, 17 and 31, respectively, when said leg is lifted towards the table-top on fastening it to the same.

It should be pointed out especially that it is not absolutely necessary to let the stop face 6, 18 and 28, respectively, surround the tenon 7, 19 and 32, respectively, on all sides, as shown in the embodiments according to Figs. 1 to 4.

Fig. 5 illustrates an embodiment wherein the stop face 36 of the leg 37 is to be found only beneath the border member 39 of a table-top 38, which member is provided in this embodiment with inclined surfaces which in vertical section are of a toothed appearance, for co-operation with corresponding surfaces on the tenon 40 of the leg 37. Fig. 5 also shows a fastening means other than a threaded spindle. This fastening means consists of a wedge 41 driven in between the side of the leg 37 remote from the border member 39 and block 42 secured to the underneath side of the table-top 38. The wedge 41 is retained in driven-in position by means of a screw 43 passing freely through an oblong hole 44 in the wedge 41, so that after loosening of the screw 43 the wedge can be driven in a further amount for compensating a possible drying out of the wood.

4

In Figs. 6 and 7 the invention is applied to a table comprising a table-top 45, two plate-shaped legs 46 and a transverse member 47 connecting the legs 46. This embodiment shows by way of example that the upper ends of the legs do not need to be introduced in recesses for attaching them, as is the case in the other embodiments shown in the drawings. The upper end of each leg 46 is formed in the same manner as that of the leg shown in Fig. 5, for cooperation with a securing member 48 fixed to the underneath side of the table-top 45. The leg 46 is pressed against the member 48 by a screw device corresponding in principle to that shown in Fig. 2.

As is evident, the invention may be realized in various ways, for which reason it must not be considered as limited solely to the embodiments shown and described. It should be observed especially that the invention may be applied to other pieces of furniture with legs than tables, e. g. chairs, sofas and cupboards. Instead of fastening each leg individually, it is naturally possible to connect the legs in pairs to a unit or subassembly that is fastened in accordance with the invention. Therefore, the expression "leg means" is used throughout this specification and the appended claims to refer to both single legs and such subassemblies consisting of two (or more) legs connected to a unit. It should be pointed out also that the stop faces 6, 28 and 36, respectively, forming angles with the inclined co-operating surfaces of the body portion of the piece of furniture and arranged on the respective leg or pair of legs can be arranged in a manner other than that shown. For instance, they can be arranged on the end of the respective leg for bearing against e. g. the underneath side of the table-top or the like.

What I claim and desire to secure by Letters Patent is:

1. A piece of furniture comprising a body portion and mountable and removable leg means, a plurality of parallel bearing surfaces on each of said leg means inclined with respect to the longitudinal direction of the associated leg means, a plurality of coacting similarly inclined bearing surfaces on said body portion, the sets of bearing surfaces being slightly displaced with respect to one another, means for exerting a force on each of said leg means obliquely to the sets of inclined coacting bearing surfaces and to the longitudinal direction of said leg means and pressing said inclined bearing surfaces together, co-operating stop surfaces on said leg means and said body portion forming angles with said inclined bearing surfaces, said stop surfaces being pressed against each other upon sliding of the sets of said bearing surfaces with respect to one another in response to said force.

2. A piece of furniture comprising a body portion and mountable and removable leg means, a plurality of parallel bearing surfaces on each of said leg means inclined with respect to the longitudinal direction of the associated leg means and arranged in a row in the longitudinal direction of the leg means, a plurality of coacting similarly inclined bearing surfaces on said body portion, the sets of bearing surfaces being slightly displaced with respect to one another, means for exerting a force on each of said leg means obliquely to the sets of inclined coacting bearing surfaces and to the longitudinal direction of said leg means and pressing said inclined bearing surfaces together, said force means being positioned substantially midway between the two outermost

ones of said inclined bearing surfaces, and co-operation stop surfaces on said leg means and said body portion forming angles with said inclined bearing surfaces, said stop surfaces being pressed against each other upon sliding of the sets of said bearing surfaces with respect to one another in response to said force.

3. A piece of furniture comprising a body portion and mountable and removable leg means, tenon means on each of said leg means, a plurality of parallel bearing surfaces on each of said tenon means inclined with respect to the longitudinal direction of the associated leg means and arranged in a row in the longitudinal direction thereof, a plurality of coacting similarly inclined bearing surfaces on said body portion, the sets of bearing surfaces being slightly displaced with respect to one another, means for exerting a force on each of said leg means obliquely to the sets of inclined coacting bearing surfaces and to the longitudinal direction of said leg means and pressing said inclined bearing surfaces together, a stop surface surrounding each said tenon means on said leg means and a stop surface surrounding a hole for each of said tenon means in said body portion, said co-operating stop surfaces forming angles with said inclined bearing surfaces and with the longitudinal direction of said leg means and being pressed against each other upon sliding of said bearing surfaces with respect to one another in response to said force.

4. A piece of furniture comprising a body portion and mountable and removable leg means, tenon means on each of said leg means, a plurality of parallel bearing surfaces on each of said tenon means inclined with respect to the longitudinal direction of the associated leg means and arranged in a row in the longitudinal direction of the associated leg means, a plurality of coacting

similarly inclined bearing surfaces on said body portion, the sets of bearing surfaces being slightly displaced with respect to one another, means for exerting a force on each of said leg means obliquely to the sets of inclined coacting bearing surfaces and to the longitudinal direction of said leg means and pressing said inclined bearing surfaces together, said force means being positioned substantially midway between the two outermost ones of said inclined bearing surfaces, a stop surface surrounding each said tenon means on said leg means and a stop surface surrounding a hole for each of said tenon means in said body portion, said co-operating stop surfaces forming angles with said inclined bearing surfaces and with the longitudinal direction of said leg means and being pressed against each other upon sliding of said bearing surfaces with respect to one another in response to said force.
